UNITED STATES PATENT OFFICE.

WILLIAM HEGLAND, OF PLENTYWOOD, MONTANA.

STAMP AND ENVELOP MOISTENER.

1,315,305.

Specification of Letters Patent. Patented Sept. 9, 1919.

Application filed June 11, 1919. Serial No. 303,312.

To all whom it may concern:

Be it known that I, WILLIAM HEGLAND, a citizen of the United States, residing at Plentywood, in the county of Sheridan and State of Montana, have invented certain new and useful Improvements in Stamp and Envelop Moisteners, of which the following is a specification, reference being had to the accompanying drawings.

10 This invention relates to devices for moistening stamps and envelopes, and particularly to that class of devices wherein a tubular liquid container is provided having a moistening element in its lower end kept moist by the liquid within the container.

The general object of my invention is to provide an envelop and stamp moistener comprising a container formed at one end with a cover and at the other end with a 20 mass of spongy material disposed within a rubber cap and carrying upon its face an absorbent element such as a piece of sponge, the rubber cap being so formed as to provide a projection which, when the moistener is 25 in use, will force the cap inward, thereby compressing the sponge within the cap and causing the water to be forced out therefrom through the perforations in the cap and onto the exterior sponge or other fibrous 30 wiper.

A further object is to provide a device of this character so constructed that it will not leak, but further so constructed that the sponge within the cap will be kept in a 35 moist condition at all times.

Another object is to provide a device of this character which is very simple in construction, relatively cheap, and which will be extremely convenient for the purpose described.

My invention is illustrated in the accompanying drawings, wherein:

Figure 1 is an elevation of my improved moistening device;

Fig. 2 is a longitudinal diagrammatic section thereof;

Fig. 3 is an under side plan view; and

Fig. 4 is a section on the line 4-4 of Fig. 2.

Referring to these drawings, 10 designates the body of the container which may be made of any suitable material and which is cylindrical and has a diameter and length such that it may be conveniently held within 55 the hand. This tubular container is bent at its opposite ends, and one end is provided

with a detachable cover 11 which may be screw-threaded or have a sliding fit with this end of the container. The opposite end of the container is connected to a somewhat 60 bulbous cap of flexible rubber 12 which may be glazed rubber, and the bottom of this rubber cap is formed with a plurality of closely disposed perforations 13.

Carried upon the outer face of the cap at 65 the bottom thereof, is a small mass of sponge 14 extending diametrically across the face of the cap and the holes 13 discharge adjacent to this piece of sponge or immediately upon it. Disposed within the lower end of the container 10, just above the upper portion of the rubber cap, is a diaphragm 15 which may be conveniently formed of cork or other suitable material and which is perforated at 16. This has a sliding fit 75 within the lower end of the container, and disposed between this diaphragm and the bottom of the cap is a mass of sponge or like absorbent material, designated 17. A very light spring 18 rests upon this cork 80 and bears at its upper end against an annular diaphragm 19, but preferably bears against a small sponge 20. The spring is a coil spring and, therefore, the center of the spongy mass will not be engaged by the 85 spring but will allow the liquid in the upper portion of the container to filter through the sponge and down onto the cork 16, and from thence the liquid will pass into the sponge 17 so that this sponge will be kept 90 sufficiently moist at all times without, however, being supersaturated.

Preferably, the cap 12 is formed on one side of the piece of sponge 14 with a projection 21 extending downward and outward away from the sponge 14, and this projection provides means whereby the flexible rubber cap may be forced inward against the sponge 17 to thus compress this sponge and cause the water to be discharged therefrom through the perforations 13 and onto the transversely extending sponge strip 14 by a pressure of the moistener against the envelop, stamp or other surface to which the moisture is to be applied. Thus, only 105 a slight pressure need be applied to the sponge 14 itself and thus this sponge may be kept relatively moist while it is being used. Were this projection 21 not provided, then pressure would come upon the sponge 110 14 and this pressure would drive the water in it out of the sponge, leaving it relatively

dry until the pressure was reduced. Of course, it will be understood that the piece of sponge 14 may be made relatively thin and narrow. The perforations 13 are so small, that while they will wet the sponge 14, yet water will not ordinarily pass out through them except when the sponge 17 is depressed.

It will be seen that my device is very simple and convenient, that it does away entirely with the unsanitary practice of "licking" stamps and envelopes, and the inconvenience of using a sponge cup for the same purpose. The device may be obviously gotten up in an attractive manner and, of course, may be made in various sizes to suit different purposes.

I claim:—

1. A moistener of the character described comprising a hollow container, a removable closure at one end of the container, and the opposite end of the container being provided with a cap of flexible material formed with small perforations, a perforated diaphragm disposed within the container adjacent the cap, and a mass of elastic, fibrous, absorbent material disposed within the cap, and a strip of absorbent, fibrous material carried upon the outside of the cap adjacent the perforations therethrough.
2. A moistener of the character described comprising a hollow container, a removable closure at one end of the container, and the opposite end of the container being provided with a cap of flexible material formed with small perforations, a perforated diaphragm disposed within the container adjacent the cap, and a mass of elastic, fibrous, absorbent material disposed within the cap, and a strip of absorbent, fibrous material carried upon the outside of the cap adjacent the perforations therethrough, the flexible cap being provided on one side of the strip of fibrous material with a projection.

3. A device of the character described comprising a hollow container having a detachable closure at one end, a somewhat bulbous, flexible, water-proof cap attached to the other end of the container and having a transversely extending line of perforations therethrough, a transversely extending strip of sponge attached to the exterior of the cap adjacent said perforations, a perforated diaphragm disposed within the lower end of the container, a mass of spongy material disposed within the cap and below the diaphragm, the cap being formed to one side of the line of perforations with a downward and outward projection.

4. A device of the character described comprising a hollow container having a detachable closure at one end, a somewhat bulbous, flexible, water-proof cap attached to the other end of the container and having a transversely extending line of perforations therethrough, a transversely extending strip of sponge attached to the exterior of the cap adjacent said perforations, a perforated diaphragm disposed within the lower end of the container, a mass of spongy material disposed within the cap and below the diaphragm, the cap being formed to one side of the line of perforations with a downward and outward projection, the body of the container being formed with an annular diaphragm intermediate its length, and a coiled spring bearing against the first named diaphragm and operatively bearing against the second named diaphragm, thereby urging the first named diaphragm downward against the sponge.

In testimony whereof I hereunto affix my signature in the presence of two witnesses.

WILLIAM HEGLAND.
